(57) **CLAIM**

The ornamental design for an accessory tool storage door for a floor care appliance, as shown and described.

DESCRIPTION

FIG. 1 is a front view of an accessory tool storage door for a floor care appliance showing our new design;

FIG. 2 is a top view thereof;

FIG. 3 is a right side view thereof; and,

FIG. 4 is a left side view thereof.

The details shown in broken lines in all views are for illustrative purposes only and form no part of the claimed design.
